LAG SCREW ANCHORING INSERT FOR A CONCRETE SLAB

Harry G. Ballou, San Leandro, Calif., assignor to Superior Concrete Accessories, Inc., Chicago, Ill., a corporation of Illinois

Application June 25, 1953, Serial No. 363,964

7 Claims. (Cl. 72—105)

The present invention relates generally to wire formed inserts for concrete slabs. More particularly the invention relates to that type of insert which is adapted to be embedded in one corner portion of a tilt-up variety concrete wall slab during formation of the latter and serves with similar inserts in the other corner portions of the slab and after hardening of the concrete as a medium whereby the slab may be detachably connected to a crane or like hoisting mechanism to the end that it may be first raised while in a horizontal position and then tilted into a vertical position next to a concrete floor slab in connection with the construction of a building.

One object of the invention is to provide a wire formed insert which is an improvement upon, and has certain inherent advantages over, previously designed inserts of the same general type and is characterized by extremely high efficiency and strength and a novel arrangement of parts.

Another object of the invention is to provide a wire formed insert which comprises as its principal components: (1) a pair of spaced apart nut-like helixes which are adapted to be positioned directly inwards of, and to extend at right angles to, one of the side surfaces of the slab with which the insert is associated, and are designed to receive the shanks of a pair of lag screws; (2) a pair of side-by-side U-shaped legs which extend between, and serve to space apart, the helixes and have the outer ends of their side parts welded to the inner or opposed portions of the helixes; and (3) two pairs of L-shaped legs which are associated with, and are disposed outwards of, the helixes, respectively, and have the outer ends of certain parts thereof welded to the outer portions of the helixes and their other parts disposed in parallel relation with the intermediate parts of the U-shaped legs.

Another object of the invention is to provide a wire formed insert of the last-mentioned character in which said other parts of the L-shaped legs are provided with V-shaped feet which, in connection with formation of the wall slab with which the insert is associated, serve to space said other parts of the L-shaped legs and the intermediate parts of the U-shaped legs inwards from the other side surface of the slab.

A further object of the invention is to provide a wire formed insert of the type and character under consideration in which the inner ends of said other parts of the L-shaped legs and the ends of the intermediate parts of the U-shaped legs have applied to them straight rigid cross wires which extend at right angles to the intermediate parts of the U-shaped legs and serve materially to enlarge the shear cone of the slab corner portion in which the insert as a whole is embedded.

A still further object of the invention is to provide a wire formed insert which is generally of new and improved construction, effectively and efficiently fulfills its intended purpose and, due to its particular construction, is capable of being produced at a comparatively low cost.

Other objects of the invention and the various advantages and characteristics of the present wire formed in-

2

sert for concrete slabs will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

10 Figure 1 is a perspective of a wire formed insert embodying the invention;

15 Figure 2 is a vertical section showing a tilt-up variety concrete wall slab positioned over a concrete floor slab and having embedded in its corner portions wire formed inserts embodying the invention;

20 Figure 3 is a similar section showing the inserts after they have been connected by way of their lag screws to a harness on a crane and also showing by way of dash-dot lines and dash-dot-dot lines the manner in which the concrete wall slab in which the inserts are embedded is first raised above the concrete floor slab and is then tilted into a vertical position wherein its lower margin abuts against the floor slab;

25 Figure 4 is a perspective showing the concrete wall slab after it has been tilted into its vertical position; and

30 Figure 5 is an enlarged vertical section on the line 5—5 of Figure 3.

The insert which is shown in Figure 1 of the drawings constitutes the preferred form or embodiment of the invention. It is designated by the reference numeral 6 and is adapted with three similar inserts 7, 8 and 9 to be embedded in a tilt-up variety concrete wall slab 10 and to form with said similar inserts a medium whereby the slab 10 may be detachably connected to a crane to the end that it may be raised and then tilted into a vertical position next to a concrete floor slab 11 in connection with the construction of a concrete building. The floor slab 11 is shown in Figures 2, 3 and 4 as resting on a fill or foundation 12 at the site where the building is to be erected. It is contemplated that in connection with fabrication of the building a rectangular horizontally extending frame 13 will be placed on the foundation 12. After the frame is suitably secured or anchored in place concrete in plastic form is poured into the bottom portion of the frame interior in order to form the floor slab. After pouring of the concrete for such slab a separator type film or layer of non-adhesive material is applied to the top surface of the concrete. Thereafter the inserts 6, 7, 8 and 9 are placed over the corner portions of the poured concrete 50 for the floor slab 11 and concrete is poured into the upper portion of the frame interior in order to form the wall slab 10. As soon as the last poured concrete hardens or solidifies the wall slab 10 with the four inserts embedded in its corner portions is in readiness to be raised and then 55 tilted into a vertical position next to the floor slab 11 as hereinafter described.

The insert 6 is a unitary structure and for the purpose of the following description of it will be considered as embedded in one corner portion of the wall slab 10 while 60 the latter is horizontally positioned over the concrete floor slab 11. It is formed of such heavy gauge wire that for practical purposes it is rigid. As its principal components the insert 6 comprises a pair of nut-like helixes 14 and 15, a pair of U-shaped legs 16 between the two helixes, a pair of L-shaped legs 17 in associated relation with the helix 14 and a pair of L-shaped legs 18 in associated relation with the helix 15. The helixes 14 and 15 are so formed that the convolutions thereof are of the same diameter and abut against one another. They extend vertically and are arranged so that the upper ends thereof are disposed directly beneath the upper side surface of the wall slab 10 and their lower ends are positioned

an appreciable distance above the bottom side surface of such slab. The interior of the helix 14 defines an internal screw thread for receiving the shank of a lag screw 19, and the interior of the helix 15 defines an internal screw thread for receiving the shank of a lag screw 20. It is contemplated that when the wall slab 10 is formed the concrete therefor will be poured into the upper portion of the interior of the frame 13 until the upper level thereof reaches the upper ends of the helixes 14 and 15. By discontinuing further pouring of concrete at this point the upper ends of the two helixes will be open to the end that the helixes will be able to receive the shanks of their respective lag screws. The U-shaped legs 16 are arranged in side by side relation but are spaced a small distance apart. They serve to hold the helixes 14 and 15 in fixed spaced apart relation and consist of horizontally extending intermediate parts 21 and vertically extending end parts 22. The intermediate parts 21 of the U-shaped legs 16 are located a small distance above the bottom side surface of the slab 10 and have the ends thereof connected to, and formed integrally with, the lower ends of the vertically extending end parts 22. The upper ends of the end parts 22 fit against, and are welded to, the inner side portions of the two helixes. The U-shaped legs 16 serve not only to hold the helixes 14 and 15 in spaced apart relation but also to cause the insert 6 as a whole to become firmly interlocked with the wall slab 10 after hardening of the concrete for the latter. The L-shaped legs 17 are located directly outwards of the helix 14 and consist of horizontally extending parts 23 and vertically extending parts 24. The vertically extending parts 24 are formed integrally with, and extend upwards from, certain ends of the horizontally extending parts 23 and have the upper ends thereof welded to the outer portion of the helixes 14. The horizontally extending parts 23 of the L-shaped legs 17 extend at right angles to one another and are disposed in the same horizontal plane as the intermediate parts 21 of the U-shaped legs 16. They are straight and extend outwards at angles of 135° with respect to the intermediate parts of the U-shaped legs. The L-shaped legs 18 are like the legs 17 and consist of straight horizontally extending parts 25 and vertically extending parts 26. The upper ends of the vertically extending parts are welded to the outer portion of the helix 15. The horizontally extending parts 25 extend at right angles to one another and lie in the same horizontal plane as the intermediate parts 21 of the U-shaped legs 16 and the horizontally extending parts 23 of the L-shaped legs 17. They are formed integrally with the vertically extending parts 26 and extend at angles of 135° with respect to the intermediate parts 21 of the U-shaped legs 16. The outer central portions of the horizontally extending parts of the L-shaped legs 17 and 18 are provided with depending V-shaped feet 27. The latter are formed of medium gauge wire and serve, in connection with formation of the wall slab 10, to space the horizontally extending parts of the L-shaped legs 17 and 18 from the bottom side surface of the slab. The upper ends of the V-shaped feet 27 fit against, and are welded to, the outer central portions of the horizontally extending parts of the L-shaped legs. In addition to the parts heretofore mentioned the insert 6 comprises a pair of straight rigid cross wires 28 and a pair of straight rigid cross wires 29. The cross wires 28 extend at right angles to the U-shaped legs 16 and have the central portions thereof resting on, and welded to, the ends of the intermediate parts 21 of the U-shaped legs. The cross wires 29 are located directly outwards of, and arranged in parallel relation with, the cross wires 28 and have the central portions thereof resting on, and welded to, the inner ends of the horizontally extending parts of the L-shaped legs 17 and 18. The cross wires 28 and 29 serve materially to enlarge or increase the shear cone of the slab corner portion in which the insert 6 is embedded. As shown in the drawings and heretofore indicated, the insert 6 is embedded in one corner portion of the wall slab 10. After the concrete for the wall slab hardens or solidifies the insert 6 is connected to an angle bracket 30 by way of the lag screws 19 and 20. The angle bracket 30 consists of a horizontally extending leg 31 and a vertically extending leg 32. The horizontally extending leg 31 of the angle bracket 30 is adapted to fit flatly against the portion of the upper side surface of the wall slab 10 under which the insert 6 is embedded and has at its ends holes 33 for receiving the shanks of the lag screws 19 and 20. The vertically extending leg 32 of the angle bracket 30 extends upwards with respect to the horizontally extending leg 31 and has a hole in its central portion. When it is desired to effect connection of the insert 6 and the angle bracket 30 the angle bracket is positioned over the wall slab 10 and then manipulated so as to bring the holes 33 in the end portions of the horizontally extending leg 31 into registry with the helixes 14 and 15. Thereafter the lag screws 19 and 20 are inserted through the holes and are then turned in the proper direction so as to connect the shanks thereof to the internal screw threads that are defined by the interiors of the helixes.

The inserts 7, 8 and 9 are the same in size and construction as the insert 6. They are embedded in the other corner portions of the wall slab 10 and are adapted to be connected to angle brackets 34 by lag screws 35. The brackets 33 are the same in design and construction as the angle bracket 30.

The inserts 6, 7, 8 and 9, as heretofore pointed out, serve as a medium whereby the wall slab 10 may be detachably connected to a crane. The crane is not illustrated in the drawings but embodies a cable supported hook-equipped block 36 from which is suspended a harness 37. The latter (see Figure 4) comprises a rigid horizontally extending harness member 38 and a pair of depending cables 39 at the ends of the member. The harness member 38 is provided with a cable arrangement 40 whereby it is connected to the hook of the cable supported block 36 of the crane. The central portions of the cables 39 extend around depending sheaves 41 on the ends of the harness member 37 and the ends of such cables are provided with eye-bolts 42 where they may be connected to the central portions of the vertically extending flanges of the aforementioned angle brackets. It is contemplated that after the harness 37 is connected to the angle brackets the wall slab 10 will be raised into the position shown in dash-dot lines in Figure 3. It is also contemplated that after the wall slab is raised it will be tilted into a vertical position wherein the lower margin of the slab will be in abutting relation with the floor slab 11 as shown in dash-dot lines in Figure 3. After the wall slab is placed in its vertical position the harness 37 and the angle brackets are removed and the slab is then held in place by any suitable brace while it is being connected to adjoining wall slabs. When the wall slab is raised by the crane the lag screws are in tension and when the slab is tilted in its vertical position the lag screws are in shear.

The herein described wire formed insert, due to its particular construction, forms an effective anchor for its lag screws regardless of whether the latter are in tension or shear. It is capable of being subjected to a comparatively heavy load without being pulled from or causing cracking or breakage of the concrete in which it is embedded. By reason of the fact that the insert includes both U-shaped and L-shaped legs the insert as a whole effectively and efficiently fulfills its intended purpose.

Whereas the insert has been described as being adapted for embedment in one corner portion of a tilt-up variety wall slab it is to be understood that it is capable of being used in any form or type of concrete slab. It is also to be understood that the invention is not to be restricted to the details set forth since these may be modified within the scope of the appended claims without departing from the spirit and scope of the invention.

Having thus described the invention what I claim as new and desire to secure by Letters Patent is:

1. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one surface of the slab, the interiors of said helixes forming internal screw threads for receiving the shanks of the lag screws, a one piece U-shaped wire leg extending between the helixes and serving to space the latter apart, said U-shaped leg consisting of a straight intermediate part and straight end parts extending at right angles to the intermediate part, the outer ends of said end parts being positioned in abutment with, and connected to, the inner side portions of the helixes, and two pairs of L-shaped wire legs associated with, and disposed outwards of, the helixes, respectively, said L-shaped legs consisting of first parts in parallel relation with the end parts of the U-shaped leg and second parts at right angles to the first parts and in substantially the same plane as the intermediate part of said U-shaped leg, the outer ends of said first parts being arranged in abutment with, and connected to, the outer side portions of the helixes, the second parts of said L-shaped legs being positioned at obtuse angles with respect to said intermediate parts of the U-shaped leg.

2. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one surface of the slab, the interiors of said helixes forming internal screw threads for receiving the shanks of the lag screws, a pair of side by side one piece U-shaped wire legs extending between said helixes and serving to space the latter apart, said U-shaped legs consisting of straight intermediate parts and straight end parts extending at right angles to the intermediate part, the outer ends of said end parts being arranged in direct abutment with, and welded to, the inner side portions of the helixes, and two pairs of L-shaped wire legs associated with, and disposed outwards of, the helixes, respectively, said L-shaped wire legs consisting of straight first parts in parallel relation with the end parts of the U-shaped legs and straight second parts at right angles to the first parts and in substantially the same plane as the intermediate parts of said U-shaped legs, the outer ends of said first parts being arranged in direct abutment with, and welded to, the outer side portions of the helixes, said second parts of the L-shaped legs being positioned at obtuse angles with respect to said intermediate parts of the U-shaped legs.

3. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one side surface of the slab, the interiors of said helixes forming internal screw threads for receiving the shanks of the lag screws, a one piece U-shaped wire leg extending between said helixes and serving to space the latter apart, said U-shaped wire leg consisting of a straight intermediate part and straight end parts extending at right angles to the intermediate part, the outer ends of said end parts being in abutment with, and welded to, the inner side portions of the helixes, and two pairs of L-shaped wire legs associated with, and disposed outwards of, the helixes, respectively, said L-shaped wire legs consisting of straight first parts in parallel relation with the end parts of the U-shaped leg and straight second parts at right angles to the first parts and in substantially the same plane as the intermediate part of said U-shaped leg, the outer ends of said first parts fitting against, and welded to, the outer side portions

of the helixes, said second parts of the L-shaped legs being positioned at obtuse angles with respect to said intermediate part of the U-shaped legs and provided with fixed wire feet extending away from the helixes and adapted to space said second parts as well as said intermediate part from the other side surface of the slab.

4. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one surface of the slab, the interiors of said helixes forming internal screw threads for receiving the shanks of the lag screws, a one piece U-shaped wire leg extending between the helixes and serving to space the latter apart, said U-shaped leg consisting of a straight intermediate part and straight end parts extending at right angles to the intermediate part, the outer ends of said end parts being arranged in abutment with, and connected to, the inner side portions of the helixes, two pairs of L-shaped wire legs associated with, and disposed outwards of, the helixes, respectively, said L-shaped legs consisting of straight first parts in parallel relation with the end parts of the U-shaped leg and straight second parts at right angles to the first parts and in substantially the same plane as the intermediate part of said U-shaped leg, the outer ends of said first parts being arranged in abutment with, and connected to, the outer side portions of the helixes and the second parts of the L-shaped legs being positioned at obtuse angles with respect to said intermediate part of the U-shaped leg, and cross wires disposed at right angles to said intermediate part of the U-shaped leg and extending across the inner ends of said second parts of the L-shaped legs.

5. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one surface of the slab, the interiors of said helixes forming internal screw threads for receiving the shanks of the lag screws, a pair of side by side one piece U-shaped wire legs extending between said helixes and serving to space the latter apart, said U-shaped legs consisting of straight intermediate parts and straight end parts extending at right angles to the intermediate part, the outer ends of said end parts being arranged in direct abutment with, and welded to, the inner side portions of the helixes, two pairs of L-shaped wire legs associated with, and disposed outwards of, the helixes, respectively, said L-shaped legs consisting of first parts in parallel relation with the end parts of the U-shaped legs and straight second parts at right angles to the first parts and in substantially the same plane as the intermediate parts of said U-shaped legs, the outer ends of said first parts being in direct abutment with, and welded to, the outer side portions of the helixes, said second parts of the L-shaped legs being positioned at obtuse angles with respect to said intermediate parts of the U-shaped legs, and cross wires extending across the ends of the intermediate parts of said U-shaped legs and welded thereto.

6. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one side surface of the slab, the interiors of said helixes forming internal screw threads for receiving the shanks of the lag screws, a pair of side by side one piece U-shaped wire legs extending between the helixes and serving to space the latter apart, said U-shaped legs consisting of straight intermediate parts and straight end parts extending at right angles to the intermediate part, the outer ends of said end parts being arranged in direct abutment with, and welded to, the inner side por-

tions of the helixes, and two pairs of L-shaped wire legs associated with, and disposed outwards of, the helixes, respectively, said L-shaped legs consisting of straight first parts in parallel relation with the end parts of the U-shaped legs and straight second parts at right angles to the first parts and in substantially the same plane as the intermediate parts of said U-shaped legs, the outer ends of said first parts being in direct abutment with, and welded to, the outer side portions of the helixes, said second parts of the L-shaped legs being positioned at obtuse angles with respect to said intermediate parts of the U-shaped legs and having welded thereto V-shaped wire feet, the apices of which extend away from the helixes and are adapted to space said second parts as well as said intermediate parts away from the other side surface of the slab.

7. As an article of manufacture, an insert adapted for embedment in a concrete slab and to form an anchor for a pair of lag screws, said insert comprising a pair of wire helixes disposed in spaced apart relation and adapted to have certain ends thereof disposed directly inwards of, and opening onto, one side surface of the slab, the interiors of said helixes forming internal screw threads for receiving the shanks of the lag screws, a pair of side by side but slightly spaced apart one piece U-shaped wire legs extending between the helixes and serving to space the latter apart, the U-shaped legs, consisting of straight intermediate parts and straight end parts extending at right angles to the intermediate part, the outer ends of said end parts side, being welded to the inner portions of 30 the helixes, two pairs of L-shaped wire legs associated

with, and disposed outwards of, the helixes, respectively, said L-shaped legs consisting of straight first parts in parallel relation with the end parts of the U-shaped legs and straight second parts at right angles to the first parts 5 and in substantially the same plane as the intermediate parts of said U-shaped legs, the outer ends of said first parts being arranged in direct abutment with, and welded to, the outer side portions of the helixes, second parts of the L-shaped legs being positioned at obtuse angles with respect to said intermediate parts of the U-shaped legs and having welded thereto V-shaped wire feet, the apices of which extend away from the helixes and are adapted to space said second parts as well as said intermediate parts away from said other side surface of the slab, inner cross wires extending at right angles to, and across the ends of, the intermediate parts of said U-shaped legs and welded to said ends of the intermediate parts, and outer cross wires disposed in parallel relation with the inner cross wires and welded to, and extending across, the inner ends of said second parts of the L-shaped legs.
